UNITED STATES PATENT OFFICE

SEVERIN HALVORSEN, OF CHICAGO, ILLINOIS, ASSIGNOR TO THE NEWSPAPER STUFFING MACHINE COMPANY, OF SEATTLE, WASHINGTON, A CORPORATION OF WASHINGTON

PNEUMATIC FEED MECHANISM

Application filed December 22, 1924. Serial No. 757,341.

My invention relates to pneumatic feed mechanisms for feeding papers or paper sections or like articles from one end of a stack or pile.

5 The objects of the invention are to provide an improved construction of pneumatic feed mechanism of the class specified; to secure rapidity and efficiency in operation; to secure simplicity of structure; and to provide a 10 mechanism particularly well adapted to feed parts or sections of a newspaper.

In the accompanying drawings Fig. 1 is a front elevation of a pneumatic feed mechanism embodying my invention;

15 Fig. 2 is a plan view of the same;

Fig. 3 is an end view looking toward the left hand end of Fig. 1;

20 Figs. 4, 5 and 6 are cross sections taken on lines 4-4, 5-5 and 6-6, respectively, in Fig. 1;

Figs. 7, 8 and 9 are views of details of construction, Fig. 7 being taken on line 7-7 in Fig. 9.

25 Referring to the drawings, the feed mechanism shown comprises means such as the uprights 1, 2 and 3 for holding a stack or pile of articles to be fed, such as newspaper sections A-A. A supporting member 4 is shown for supporting papers or other articles, but this support does not extend entirely underneath the bottom paper, but only for the right hand portion of the same, as shown in Figs. 4 and 5, leaving space underneath the left hand portions of said paper, through which the folded edges of the papers or paper sections may pass.

These folded edges of the papers are supported and released by two sets of supporting fingers 5-5 and 6-6. The fingers 5-5 have hooked or bent ends 7 adapted to slide underneath the papers A and said fingers are mounted on blocks 8 carried by a rock shaft 9 which has a crank arm 10 pivotally connected with a link 11 which latter is carried by a forked sliding member 12 actuated by a cam 13 on a rotary shaft 14, so that the rotation of shaft 14 causes cam 13 to act against roller 15 and so cause link 11 to swing rock shaft 10 and rock shaft 9 so as to swing

fingers 5 back and forth underneath the folded edges of paper sections A.

The other fingers 6 are carried by blocks 17 on the rotary shaft 18 and shaft 18 is rocked by a crank arm 19 connected with a 55 sliding member 20 having a forked end 21 straddling rotary shaft 22 carrying cam 23, said member 20 also having a roller 24 actuated by cam 23, so that member 20 will be reciprocated by rotation of shaft 22 and will 60 cause swinging movement of fingers 6.

The operating mechanisms for these two sets of the swinging fingers 5-5 and 6-6 are arranged so that the pile will be normally supported by fingers 7-7 as shown in Fig. 65 5, but these fingers will be swung away to release the lowermost paper section, and as soon as this section is released the fingers 6-6 will be swung up to engage the edge of the next lowermost paper, and then the fingers 5-5 will be swung back to make full engagement with said second paper which becomes the lowermost paper and so supports 70 the same and the pile.

Pneumatic feed devices or suckers 26-26 75 are mounted on a rotary tubular member or pipe 27 located below the stack or pile of papers A between the ends of fingers 7 and the end support 4. These suckers 26 are adapted to engage the lowermost paper section A when it is released by fingers 7, and pull the same down as shown in Fig. 5. Pipe 27 is carried by bearing 28 mounted on a sliding carriage 29, said carriage 29 being mounted to slide on guideways 30. Carriage 80 29 is reciprocated by swinging member 31 mounted on a rock shaft 32 and having a forked end which embraces a nut 33. Shaft 32 carries pinion 34 meshing with rack 35 carried by reciprocating member 36 mounted 85 on rotary drive shaft 37, which latter is provided with a cam 38 adapted to act on roller 39 so that cam 38 will reciprocate member 36 and thereby rock swinging member 31 to reciprocate carriage 29. Idle roller 40 holds 90 rack 35 in position.

Tubular or pipe member 27 carrying sucker devices 26 is provided with a pinion 41 meshing with stationary rack 42 (Fig. 6), whereby reciprocation of carriage 39 will 100

cause rotation of pipe 27 as the carriage is reciprocated and thus suckers 26 will swing downwardly and be moved bodily backwardly so as to effect such downward swinging and backward movement on the part of the bottom paper section acted on by the suckers 26, as shown in Fig. 5.

Pneumatic pressure to the suckers 26 is controlled by a valve device 44 (Figs. 3, 7, 8 and 9). This consists of a flat block 45 to which is extended a pipe 46 leading from the end of pipe 27 carrying the sucker devices 26. Another pipe 47 leads from block 45 to a pressure reducing apparatus by which an exhaust condition is produced for the suckers 26. The block 45 is provided with two channels 48 and 49, which nearly meet each other but do not quite meet, their ends being separated by a solid portion 50 (Fig. 7). A rotary plate 51 is mounted in front of the block 45 and provided with a recess 52 adapted to afford communication between the end portions of the channels 48 and 49. The plate 51 is mounted for rotary movement and is rocked by a link arm 53 connected at 54 with a rocker arm 55, pivotally mounted at its lower end 56. Rocker arm 55 is actuated by a cam 57 on cam shaft 14, said cam 57 cooperating with a roller 58 carried by arm 55. Thus cam 57 will cause arm 55 to actuate link 53 and the latter in turn will actuate rotary plate 51 and so establish and disestablish exhaust connection between exhaust pipe 47 and sucker supply pipe 46 which latter contains a slidable pipe 60 running to tubular member 61 containing one end of sucker carrying pipe 27, it being thus seen that sucker carrying pipe 27 carrying suckers 26 may thus be moved transversely by the movement of carriage 29 and also may be turned in tubular member 61 and bearings 62-62, so as to permit downward and backward movement of the paper section by the suckers, and during such bodily backward and forward movement and also during such rotary movement exhaust or pneumatic connection is maintained with said sucker pipe 27 and suckers 26 through rotary tubular connection 61 and sliding tubular member or pipe 60 sliding in pipe section 46. Control of pneumatic pressure in the suckers 26 is effected by the rocker arm 55 and link 53 actuating valve member 51 so that suction or exhaust is established in suckers 26 when they are in position to engage bottom paper section A, as shown in Fig. 4, and such suction or exhaust is cut off from suckers 26 after the bottom paper section is drawn down, but before it reaches the position shown in Fig. 5.

After paper section A is drawn down it is engaged by a rotary segment 65 mounted on rotary shaft 66, the front face 67 of said segment 65 striking the depressed edge of bottom paper section and swinging the same downwardly so that it will move toward roll

68 and will pass said roll 68 and cylindrical surface of segment 67 and so be fed downwardly by said segment 65 and feed roll 68. Another feed roll 70 is located below roll 68 and adjacent segment 65 so that the paper section may be fed in between said roll 70 and segment 65 be further advanced by the same. A pair of exit rolls 71 and 72 are located somewhat below and to one side of segment 65 so as to receive the paper from roll 70 and feed it out to any desired place, either to some other mechanism in the machine or from the machine itself.

Shaft 66 carrying segment 65 also carries gear 73 meshing with pinion 74 on shaft 68a carrying roll 68 and said gear 73 also meshes with gear 75 carried by shaft 70a carrying roll 70, whereby segment shaft 66 drives rolls 68 and 70. Roll shafts 71a and 72a carrying rolls 71 and 72 respectively, are provided with pinions 76 and 77, the former of which meshes with gear 73 on segment shaft 66 and the latter of which meshes with pinion 76, whereby segment shaft 66 drives rolls 71 and 72 also.

Roll 68 is preferably mounted for elastic or yielding adjustment to permit paper sections of different thickness to pass between it and segment 65, such adjustment consisting in mounting shaft 68a in a slideway 80 subject to pressure of a spring 81 tending to force roll 68 toward segment 65 but yielding as required by thickness of paper section. Roll 70 is also yieldingly mounted as by mounting shaft 70a in a slideway bearing 82 controlled by a spring 83 carried by swinging frame 84 pivoted at 85 and having an arm 86 controlled by a spring 87 so that shaft 70a and with it roll 70 may have ample adjustment for accommodating various thicknesses of paper. Also roll 71 is adjustable with reference to roll 72, as by mounting roll shaft 71a in a slideway bearing controlled by spring 89 permitting sliding up and down movement of roll 71.

For guiding paper from roll 68 to roll 70, and from roll 70 to exit rolls 71 and 72, a swinging guide member 90 is provided having guide flanges or members 91 and 92, the former to guide papers from roll 68 to roll 70 and the latter to guide them from roll 70 to exit rolls 71 and 72. This member 90 is pivotally mounted on rock shaft 85, which latter is provided with a handle 94, Fig. 1, by which member 90 may be swung down to get it out of the way in case papers become jammed between segment 65 and rolls 68 and 70, and then fed outwardly to another part of the machine, or to a set stack or pile of exit rolls 71 and 72.

It will be understood that changes and modifications may be made without departing from the spirit of the invention.

What I claim is:

1. The combination with means for sup-

porting a stack or pile of articles, said supporting means including movable devices, movable to support and release one edge of said articles, pneumatic means for drawing 5 down the released edge of the lowermost article, means for operating said pneumatic means, said pneumatic means being mounted for bodily movement below the stack or pile and for rotative movement during such bodily 10 movement, a segmental roll for acting on the released edge of said lowermost article to swing the same further downwardly and backwardly and a feed roll cooperating with the said segmental roll to engage the downwardly and backwardly swung edge of said 15 article and feed the same.

2. The combination with means for holding and supporting a stack or pile, including swinging fingers for insertion below one edge 20 of the articles in the stack or pile, pneumatic feeding mechanism comprising sucker devices mounted for bodily movement underneath the stack or pile and also for rotative movement during such bodily movement, rotating segmental roll arranged to act upon the edge of a released article and swing the same downwardly and backwardly, and a feed roll cooperating with said rotary segment. 25

30 3. The combination with means for supporting one side of a stack or pile of articles, of fingers for supporting the other side of said articles and releasing the lowermost article, a sliding carriage carrying a rotary tubular member provided with depending suckers adapted to engage and draw down the lowermost article when released, means by which said tubular member is rotated when the sliding carriage is reciprocated, a rotary segment arranged and adapted to act upon the released edge of said lowermost article, and a roll cooperating with said rotary segment. 35

40 4. The combination with means for supporting one side of a stack of articles, two sets of fingers for supporting the other side of the same and releasing the lowermost article, a sliding carriage carrying a rotatable tubular member provided with suckers which 45 are adapted to engage and draw down the released edge of said lowermost article, a feed cooperating with said rotary segment, a pipe leading to said tubular sucker carrying member and means for controlling said pipe. 50

55 5. The combination with means for supporting one side of a stack of articles, two sets of fingers for supporting the other side of the same and releasing the lowermost article, a sliding carriage carrying a rotatable tubular member provided with suckers which are adapted to engage and draw down the released edge of said lowermost article, a feed 60 cooperating with said rotary segment, a pipe leading to said tubular sucker carrying member and means for controlling said pipe, said 65

means comprising a rocker arm link connected with said pipe and a cam for actuating said rocker arm. 70

6. In a device of the class specified, two sets of fingers for supporting the end portions of articles forming a pile, both of said sets of fingers being mounted at the end of the articles to be supported and being supported for movement into and out of position below said articles. 75

7. In a machine of the class specified, two sets of fingers arranged for cooperation with the ends of articles forming a pile, the fingers of both sets being mounted on parallel rock shafts extending crosswise of the articles in said pile, whereby the rocking of said shafts will swing said fingers into and out of position underneath said article ends. 80

8. The combination of means for supporting one side of a stack of articles, fingers for supporting the other side of the stack and intermittently releasing the lowermost article, pneumatic mechanism for drawing down the released side of a lowermost article, means for engaging said drawn down side and swinging the same downwardly and backwardly, a plurality of feed rolls for feeding said article and means for guiding the article from one feed roll to another. 85

9. The combination of means for supporting one side of a stack of articles, fingers for supporting the other side of the stack and intermittently releasing the lowermost article, pneumatic mechanism for drawing down the released side of a lowermost article, means for engaging said drawn down side and swinging the same downwardly and backwardly, a plurality of feed rolls for feeding said article and means for guiding the article from one feed roll to another, 90 said guiding means comprising a pivoted member having guiding surfaces for guiding the article and means for swinging said member about its pivot. 95

10. The combination of a support for one side of the stack, fingers for supporting the other side of the stack and releasing the lowermost article, a sliding carriage carrying a rotatable tubular member provided with depending suckers, means for reciprocating said carriage, rack mechanism for rotating said tubular member when the carriage is reciprocated, a rotatable segment for engaging the member drawn down by the suckers and swinging the same downwardly and backwardly, and a feed roll cooperating with said rotatable segment. 110 100 105

11. The combination of a support for one side of the stack, fingers for supporting the other side of the stack and releasing the lowermost article, a sliding carriage carrying a rotatable tubular member provided with suckers, means for reciprocating said carriage, rack mechanism for rotating said tubular member when the carriage is reciprocated, 115 120 125 130

- a rotatable segment for engaging the member drawn down by the suckers and swinging the same downwardly and backwardly, a plurality of feed rolls cooperating with said rotatable segment and a pivoted guide member for guiding the article from one feed roll to another.
12. The combination of a support for one side of the stack, fingers for supporting the other side of the stack and releasing the lowermost article, a sliding carriage carrying a rotatable tubular member provided with suckers, means for reciprocating said carriage, rack mechanism for rotating said tubular member when the carriage is reciprocated, a rotatable segment for engaging the member drawn down by the suckers and swinging the same downwardly and backwardly, a plurality of feed rolls cooperating with said rotatable segment, a pivoted guide member for guiding the article from one feed roll to another, and a pair of exit rolls, said guiding member having means for guiding the article to said exit rolls.
13. Means for reciprocating a travelling carriage carrying a rotatable tubular member provided with suckers, said means comprising a pivoted member having a sliding connection with said carriage and mounted on a rock shaft and a rack and pinion arrangement for rocking said shaft.
14. The combination of a reciprocating carriage carrying a rotatable tubular member provided with suckers, rack and pinion mechanism for turning said tubular member when the carriage is reciprocated, means for reciprocating the carriage, and a pipe connection to said tubular member, said pipe connection having a slidable section to permit reciprocation of said tubular member with the carriage.
15. The combination of a reciprocating carriage carrying a rotatable tubular member provided with suckers, rack and pinion mechanism for turning said tubular member when the carriage is reciprocated, means for reciprocating the carriage, a pipe connection to said tubular member, said pipe connection having a slidable section to permit reciprocation of said tubular member with the carriage, a valve in said pipe connection and means for actuating said valve to establish and disestablish an exhaust condition in said suckers.
16. The combination of a reciprocating carriage carrying a rotatable tubular member provided with suckers, rack and pinion mechanism for turning said tubular member when the carriage is reciprocated, means for reciprocating the carriage, a pipe connection to said tubular member, said pipe connection having a slidable section to permit reciprocation of said tubular member with the carriage, a valve in said pipe connection and means for actuating said valve to establish and disestablish an exhaust condition in said suckers, said valve actuating mechanism comprising a swinging arm link connected with said valve and a cam for actuating said swinging arm.
17. The combination with the slidable carriage carrying a rotatable tubular member provided with suckers, of a pipe extending to said tubular member and a valve arrangement for controlling exhaust in said pipe, said valve arrangement comprising a valve block having channels whose ends approach but do not meet and a rotary valve having a recess adapted to connect and disconnect said channels.
18. The combination with the slidable carriage carrying a rotatable tubular member provided with suckers, of a pipe extending to said tubular member and a valve arrangement for controlling exhaust in said pipe, said valve arrangement comprising a valve block having channels whose ends approach but do not meet and a rotary valve having a recess adapted to connect and disconnect said channels, and means for actuating said valve comprising a rocker arm link connected with the valve and a cam for actuating the rocker arm.
19. Means for adjustably supporting a feed roll comprising a pivoted frame 84 having a slidable bearing 82 for a feed roll shaft, a spring 83 controlling said bearing, said frame having an arm 86 and a spring 87 controlling said arm 86.
20. The combination with means for supporting one side of a stack of articles, fingers for supporting the other side and releasing the lowermost article, a reciprocating carriage arranged below the stack and carrying a rotatable tubular member provided with depending suckers, means for reciprocating the carriage, a rack and pinion arrangement for rotating the tubular member when the carriage is reciprocated, a rotary segment arranged to cooperate with the suckers and a pair of feed rolls arranged to cooperate with the rotary segment.
21. The combination with means for supporting one side of a stack of articles, fingers for supporting the other side and releasing the lowermost article, a reciprocating carriage arranged below the stack and carrying a rotatable tubular member provided with suckers, means for reciprocating the carriage, a rack and pinion arrangement for rotating the tubular member when the carriage is reciprocated, a rotary segment arranged to cooperate with the suckers, a pair of feed rolls arranged to cooperate with the rotary segment, and a pair of exit rolls arranged to cooperate with said first mentioned rolls.
22. The combination with means for supporting one side of a stack of articles, fingers for supporting the other side and re-

leasing the lowermost article, a reciprocating carriage arranged below the stack and carrying a rotatable tubular member provided with suckers, means for reciprocating the carriage, a rack and pinion arrangement for rotating the tubular member when the carriage is reciprocated, a rotary segment arranged to cooperate with the suckers, a pair of feed rolls arranged to cooperate with the rotary segment, a pair of exit rolls arranged to cooperate with said first mentioned rolls, and a guide member for guiding the article from one of the first mentioned rolls to the other and from said rolls to the exit rolls.

23. Means for reciprocating a traveling carriage carrying sucker devices, said means comprising a pivoted member having a sliding connection with said carriage and having a gear operable by a rack.

24. The combination with a reciprocating carriage, carrying sucker devices, of a slideable pneumatic connection for said sucker devices, said pneumatic connection being adapted to permit the reciprocation of said carriage, valve mechanism for controlling said pneumatic connection, and means for actuating said valve mechanism in accordance with the reciprocation of said carriage, said actuating mechanism comprising a pivotally mounted arm, a cam for actuating the same and a link connection between said pivotally mounted arm and the valve mechanism, said arm being adapted for adjustable connection with said link.

25. The combination with a reciprocating carriage carrying a rotary tubular member provided with depending sucker devices, a slideable pneumatic connection for said tubular member, said pneumatic connection being adapted to permit the reciprocation of the carriage and also adapted to permit the rotation of said member.

26. The combination with a reciprocating carriage carrying a rotary tubular member provided with sucker devices, a pneumatic connection for said tubular member, said pneumatic connection having a slideable section to permit reciprocation of the carriage and also having a rotatable connection to permit rotation of the rotary member.

27. In a device of the class specified, the combination with pneumatic devices for engaging and separating an endmost article in the stack, said pneumatic devices being mounted for bodily movement and also for rotative movement during such bodily movement, a device for acting on the released edge of such lowermost article to further separate the same, and a gripping roll cooperating with said device.

28. In a machine of the class specified, the combination of pneumatic suckers for engaging and acting upon an endmost article, slideable means for bodily moving said suckers relatively to said article and also for swing-

ing them in their bodily movement, a rotary segment adapted to engage the released edge of such endmost article, and a gripping roll arranged to cooperate with said segment.

29. In a machine of the class specified, the combination of pneumatic suckers for engaging and acting upon the endmost article, means for bodily moving said suckers relatively to said article and also for swinging them in their bodily movement, a rotary segment adapted to engage the released edge of such endmost article, a gripping roll arranged to cooperate with said segment, and a feed roll arranged to receive said article between itself and said segment.

30. In a machine of the class specified, the combination of pneumatic suckers for engaging and acting upon the endmost article, means for bodily moving said suckers relatively to said article and also for swinging them in their bodily movement, a rotary segment adapted to engage the released edge of such endmost article, a gripping roll arranged to cooperate with said segment, a feed roll arranged to receive said article between itself and said segment, and discharge rolls arranged to receive said article from said segment and feed roll.

31. The combination of a reciprocating carriage carrying a rotatable tubular member provided with sucker devices, means for rotating said member as the carriage reciprocates, a rotary segment arranged to engage the article preliminarily separated by the suckers, a gripping roll cooperating with said segment, and a feed roll to receive the article between itself and said segment.

32. The combination of a reciprocating carriage carrying a rotatable tubular member provided with sucker devices, means for rotating said member as the carriage reciprocates, a rotary segment arranged to engage the article preliminarily separated by the suckers, a gripping roll cooperating with said segment, a feed roll to receive the article between itself and said segment, and discharge rolls to receive the article from said feed roll and segment.

33. The combination with the article engaging and advancing means of a guideway mounted for bodily movement out of the way so as to permit the removal of an article in case of a jam.

34. The combination with feed rolls of a bodily removable guideway and means whereby said guideway may be moved out of guiding position to allow withdrawal of the articles.

35. The combination with feed rolls of a bodily removable guideway and means whereby said guideway may be moved out of guiding position to allow withdrawal of the articles, said guideway being pivoted at one end so that its opposite end may swing out of the way.

36. The combination with a reciprocating carriage carrying a rotatable tubular member provided with laterally extending pneumatic sucker devices, said carriage being mounted for reciprocation lengthwise of the endmost article underneath and close to the same so as to serve as a receding support for said endmost article as the same is separated from the other articles, and a rotary segment and gripping roll cooperating with said sucker devices to engage and grip the separated article and withdraw the same from the pile or stack.

In witness whereof, I hereunto subscribe my name this 15th day of December, A. D. 1924.

SEVERIN HALVORSEN.
